UNITED STATES PATENT OFFICE.

JOZO RASTIJA, OF AKRON, OHIO.

SWINGING BERTH FOR SHIPS.

1,245,769.

Specification of Letters Patent.

Patented Nov. 6, 1917.

Application filed December 14, 1916, Serial No. 136,964. Renewed October 4, 1917. Serial No. 194,806.

To all whom it may concern:

Be it known that I, Jozo RASTIJA, a subject of the King of Hungary, residing at Akron, in the county of Summit and State 5 of Ohio, have invented certain new and useful Improvements in Swinging Berths for Ships, of which the following is a specification.

This invention relates to new and useful 10 improvements in swinging berths for ships.

The primary object of the invention is the provision of an arrangement of superposed berths adapted for use upon ships, the same being independent for universal swinging 15 movements whereby the berths substantially maintain their parallel horizontal positions regardless of the rolling movements of the ship.

A further object of the device is the provision of a suspended arrangement of berths 20 adapted for free oscillation in different directions for maintaining the normal equilibrium of the berths thereby assisting in preventing seasickness and imparting comfort 25 to the occupants.

A still further object of the device is the provision of a swinging berth that is easy and inexpensive to manufacture and can be readily moved about when desired, and having 30 a plurality of sleeping portions.

In the drawings forming a part of this application and in which like-designating characters refer to corresponding parts throughout the several views:

35 Figure 1 is a side elevation of the device partially broken away,

Fig. 2 is a top plan view of the same,

Fig. 3 is an end elevation thereof,

40 Fig. 4 is a vertical transverse sectional view taken upon line IV—IV of Fig. 1.

Fig. 5 is a detailed view of a portion of one of the supporting members, illustrated by dotted lines, in its tilted position,

45 Fig. 6 is a perspective view of an end portion of one of the frame members, and Fig. 7 is a perspective view of an upper end portion of the suspended member.

The present device broadly consists of a portable mounting frame 10 having a suspended member 11 pivotally attached substantially centrally thereto and provided with a plurality of sleeping berths herein illustrated as an upper berth 12 and a lower berth 13. The arrangement hereinafter de-

scribed is such that the two berths 12 and 13 will be maintained substantially level regardless of a slight tipping of the frame 10 in any direction.

The frame 10 is formed of upright corner posts 14 which, taken with upper and lower 60 cross braces 15 arranged between the said posts at the opposite ends of the device, form rectangular end members. The said braces are secured to the posts 14 by means of bolt members 16. Side rails 17 are provided for parallel arrangement upon the braces 15, the side rails having end notches 18 and overlying hooks 19 forming sockets 20, adapted for positioning over the braces 15, whereby the rails are removably secured 70 between the end members of the frame 10.

A beam 21 is transversely mounted centrally of the upper rails, having depending brackets 22 carried thereby. The suspended member 11 is swingingly attached to the 75 brackets 22, a rectangular top member 23 being hinged to the said brackets by pintles 24 arranged centrally of the top member. A supporting strip 25 is centrally pivoted as at 26 downwardly of the ends 27 of the top 80 member 23, the said berths 12 and 13 being swingingly suspended from the said strip 25.

Each of the berths consists of a flexible mattress or bottom member 28 attached to side bars 29 as well as head and foot bars 85 30. Metallic rods 31 pivotally connect the outer ends of the bars 30 of the upper berth 12 with corresponding ends of the strips 25, while similar rods 31 connect corresponding ends of the end bar 30 of the two berths 12 90 and 13 pivotally together. A rail 32 is provided around each of the berths, being supported by the rods 31, having a central parting rail 33 to divide each berth into two sections and an end connection 34 attached 95 to the rail bar of the end 30.

From this detailed description of the device it will be seen that the top member 23 is free to oscillate longitudinally of the frame 10, while the end strips 25 may freely 100 swing laterally of the top member and frame, and the berths 12 and 13 may freely swing in any direction by means of the pivotal connections 35 between the upper rods 31 and the strips 25. The frame 10 may be 105 positioned upon the deck 36 of a ship and be readily moved about, while the berths 12 and 13 and the occupants thereof are nor-

mally maintained horizontal, regardless of the tipping of the ship or the movements of the said frame.

What I claim as new is:—

- 5 1. A device of the class described comprising a portable mounted frame having detachable upper and lower side rails, a transverse beam carried by the upper rails, brackets suspended from said beam within the frame, a rectangular top centrally pivoted within the said brackets, end strips pivoted to the ends of the said rectangular top outwardly thereof, supporting rods freely swingingly attached to the opposite ends of the said strips, and a plurality of berths pivotally suspended from the said rods and swingingly attached together.

2. A device of the class described comprising an upright frame, a rectangular top member pivoted within the said frame, strips centrally pivoted to the opposite ends of the said top member, an upper berth having end bars, supporting rods pivotally connecting the outer ends of said bars and strips, a railing for said berth carried by said rods, a longitudinal parting member carried by the railing, connections between the said end bars and the railing, and a lower berth arranged in parallelism beneath said upper berth, pivotally suspended from the opposite ends of the end bars of the upper berth.

In testimony whereof I affix my signature.
JOZO RASTIJA.
